Patented Mar. 7, 1916.

UNITED STATES PATENT OFFICE.

ALTON D. HARMON, OF CAMBRIDGE SPRINGS, PENNSYLVANIA.

CALCULATING-MACHINE.

1,174,315.

Specification of Letters Patent.

Patented Mar. 7, 1916.

Application filed September 27, 1915. Serial No. 52,835.

To all whom it may concern:

Be it known that I, ALTON D. HARMON, a citizen of the United States, residing at Cambridge Springs, in the county of Crawford and State of Pennsylvania, have invented certain new and useful Improvements in Calculating-Machines; and I do hereby declare the following to be a full, clear, and exact description of the invention, such as will enable others skilled in the art to which it appertains to make and use the same.

This invention relates to calculating machines, for adding and subtracting numerals; and it consists in certain improvements to the machine for which a patent was issued to me on April 20, 1915, No. 1,136,797, as hereinafter fully described and claimed.

In the drawings, Figure 1 is a front view 20 of a calculating machine constructed according to the present invention. Fig. 2 is a detail view of a portion of the back plate. Fig. 3 is a cross-section through the machine, taken on the line $x-x$ in Fig. 1. Fig. 25 4 is a longitudinal section, taken on the line $y-y$ in Fig. 1. Fig. 5 is a detail front view of one of the slides. Fig. 6 is a detail front view of one of the carrying signals. Fig. 7 is a detail sectional view of a portion 30 of the back plate, taken on the line $z-z$ in Fig. 2, and drawn to an enlarged scale, and showing a modification.

The machine is preferably constructed of thin light metal, but other approved material may be used. The back plate B of the machine is provided on its upper side with projecting guide ribs b arranged parallel to each other and preferably struck up from the surface of the metal.

40 The slides C are interchangeable and they have slots c in their backs which engage with the ribs b. The slides rest on the back plate, and the ribs keep the side edges of the slides from rubbing against each other. 45 Each slide has 18 stylus holes in it. The lower 9 holes are distinguished from the upper 9 holes in any convenient way, and in the example shown the lower holes are square and the upper holes are round. All 50 the holes are arranged at equal distances apart, and the lower holes are arranged out of line with the upper holes. The back plate B has ratchet-shaped toothed racks formed in it. The racks e are arranged under the lower holes d, and their teeth point in the opposite direction from those of the racks

e' which are arranged under the holes d'. When a stylus is inserted in the holes d its point engages with the teeth e, and the slide can be slid downwardly but not upwardly. 60 In the same manner the slides can be slid upwardly by stylus inserted in the holes d', but cannot be slid downwardly. In a simple form of the machine these racks are dispensed with, and then the holes d and d' can 65 be placed in line with each other.

The holes d and d' are arranged in one side portion of each slide, and its other side portion is provided with a row of index numerals E, from 0 to 9 inclusive. These 70 numerals are arranged adjacent to the stylus holes, and the numeral 2 is arranged opposite the bottom stylus hole of the series d. The face plate F extends over all the slides, and is secured to the back plate in any convenient way. The face plate is preferably provided with sides f having inwardly projecting flanges f', and the back plate is 75 slideable on the flanges f' between the sides f. The face plate has also a top end plate k' 80 which limits the upward sliding movement of the back plate, and positions it correctly. The bottom portion of the face plate has an offset portion k which extends beyond its sides f, and which is provided with eight 85 holes h through which the index numerals E of the slides may be seen. By making the part k offset from the front plate the index numerals can be read with facility, as the part k is adjacent to the faces of the slides 90 and it does not cast shadows on them which would make the numerals hard to read, and it also enable a sufficient space for signal mechanism to be provided between the face plate and the slides. This signal mechanism 95 will be fully described hereinafter. The end plate k' at the top of the machine positions the back plate. The slides and the back plate are removable at the bottom of the machine, and can be slid out of it at any 100 time so as to give free access to the signal mechanism.

The face plate F has a series of parallel slots g, one for each slide, and arranged so as to expose the stylus holes in the slides. 105 Each bar formed by the slots g has a series of numerals J, 1 to 9 inclusive, marked on it, and arranged at the same distances apart as the stylus holes. The sight holes h are positioned so that when the cipher 0 on 110 each slide is visible, as shown in Fig. 1, the lowest stylus hole of the series d is oppo-

site the numeral 1 of the series of numerals J on the face plate.

The bottom ends of the slides C are flush with the bottom end of the back plate and the bottom edge of the offset portion k of the face plate when all the slides are set to zero as shown in Fig. 1, and the setting of the slides to zero is accomplished by merely pressing all of them against any convenient stationary object, so that they are all set to zero simultaneously.

Stops m for limiting the motions of the stylus are provided at the lower ends of the slots g , and are formed by the shoulder i 15 between the face plate and its offset portion k . Stops n are provided at the upper ends of the slots g , and are formed by the edge of a stop bar N which is secured to the underside of the face plate. This stop 20 bar has notches which form teeth n' which project beyond the upper ends of the slides when the slides are moved downwardly to their full extent, and they prevent the upper ends of the slides from springing upwardly and catching against the stop bar. The stops n may be flush with the upper 25 ends of the slots g or they may project a little beyond them. The object of using a stop bar instead of using the ends of the 30 slots as stops is to form a more positive stop for the point of the stylus.

When the ends of the slots form the stops the point of the stylus is frequently pushed up too far, as the stylus is usually held in an inclined position and its point will project under the face plate if the stop bar is not used. The stop bar also stiffens the face plate, and prevents it from being crushed or bent when the machine is in use.

Carrying signals are provided similar to those in the patent hereinbefore mentioned. The levers p and s of the carrying signals have their adjacent ends articulated together, and their middle parts are pivoted 45 on pins p' and s' respectively which project from the bars of the face plate. The upper lever p has teeth t and t' on opposite sides of its top end, and the lower lever s has a tooth w which projects from 50 the left hand side of its bottom end.

Fig. 6 shows a carrying signal in its normal position, the bars of the face plate being shown in dotted lines. The teeth t and w are signal teeth, and when the stylus 55 strikes the tooth t' it turns the levers on their pivots and exposes the signal teeth at the next left hand slot.

In order to prevent the slides from sliding too freely, and also to prevent the signals from moving pivotally too freely, and to guard against accidental displacements of these parts when the device is in use, double-ended leaf springs R are mounted loosely on the pivot pins p' and s' between 60 the slides and the signals. The end por-

tions of these springs are curved or inclined so that they bear on the slides, and their middle parts bear against the signal levers.

The machine is used for adding and for 70 subtracting exactly the same as fully described in the hereinbefore mentioned patent. The stylus is inserted in the stylus hole of a suitable slide opposite the numeral on the face plate which is to be 75 added or subtracted, and the slide is slid in an appropriate direction until the stylus strikes the stop in its path. Each time a stylus strikes a tooth t' and operates a signal, an additional 1 must be registered by 80 the stylus by means of the next adjacent left hand slide. This moves back the tooth w and resets the signal.

The sum of the numerals added together by means of the slides is exhibited through 85 the sight holes h at the lower part of the machine. The provision of the offset portion k on the face plate enables the numerals on the slides to be read with facility as the offset portion comes nearer the 90 face of the slides than the main portion of the face plate.

In the modification shown in Fig. 7, a stop bar is not used, and lugs N' are formed on the face plate which project downwardly from the upper ends of the slots and form stops which prevent the point of the stylus from being pushed under the face plate. These lugs also engage with the end portions of the slides when slid 100 downwardly to their full extent so that the upper end portions of the slides cannot spring upwardly and catch against the stops, or spring over the tops of the guide 105 ribs of the back plate.

What I claim is:

1. In a calculating machine, a face plate provided with slots and having at one end of the slots a stop shoulder for the stylus and an offset portion, said offset portion being arranged parallel to the face plate and provided with sight holes, a back plate, and adding slides movable in the space between the offset portion and the back plate and having their surfaces arranged in close proximity to the offset portion so that their numerals are clearly visible through its sight holes, a chamber for signal mechanism being formed between the face plate and the slides.

2. In a calculating machine, a face plate provided with parallel slots, a back plate secured to the face plate and provided with racks having ratchet-shaped teeth, and slides movable in the space between the said plates and having stylus holes arranged over the racks so that the point of the stylus may engage with the rack teeth and prevent the slides from being moved in the wrong direction.

3. In a calculating machine, a face plate provided with parallel slots, a back plate secured to the face plate and provided with two series of racks having ratchet-shaped 5 teeth, the teeth of one series being arranged in the reverse direction from the teeth of the other series, and slides movable in the space between the said plates and having two series of stylus holes arranged over the 10 respective series of racks.

4. In a calculating machine, a face plate provided with parallel slots, a stop bar secured to the underside of the face plate at the upper ends of the slots and forming 15 stops for the stylus, a back plate, and slides arranged in the space between the said plates and provided with stylus holes, the faces of the slides being adjacent to the underside of the stop bar so that the point of the stylus 20 cannot be pushed under it.

5. In a calculating machine, a face plate provided with parallel slots, a stop bar secured to the underside of the face plate at the upper ends of the slots and forming 25 stops for the stylus and having teeth which project between the slots, a back plate secured to the face plate, and slides arranged under the stop bar and in the space between the said plates and provided with stylus 30 holes, said teeth being arranged to overlap the upper ends of the slides when the slides

are moved downwardly to their full extent and the faces of the slides being adjacent to the stop bar so that the point of the stylus cannot be pushed under it. ³⁵

6. In a calculating machine, a face plate provided with parallel slots, slides movable under the face plate and provided with stylus holes, a carrying signal pivoted under the face plate between two adjacent slots 40 and having lateral projections at its opposite end portions, a back plate under the slides, and a flat spring arranged between the carrying signal and the face of one of the slides and operating to press the slide 45 against the back plate and the signal against the front plate so as to prevent the accidental displacement of the slide and signal.

7. In a calculating machine, a face plate provided with slots, adding slides movable 50 longitudinally under the slots, carrying signals pivoted under the face plate between its slots, a back plate under the slides, and flat springs mounted on the pivots of the carrying signals and arranged between the 55 carrying signals and the faces of the slides and operating to press the signals toward the face plate and the slides toward the back plate.

In testimony whereof I have affixed my ⁶⁰ signature.

ALTON D. HARMON.
